EDWARD A. CUNNIFF, OF WALTHAM, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed June 24, 1927. Serial No. 201,070.

This invention relates to filling replenishing looms and is more particularly directed to the feeler mechanism employed in such looms to effect a change of filling prior to complete exhaustion of the filling in the shuttle.

It is now the ordinary practice to provide filling replenishing looms with a feeler mechanism for controlling the replenishment of filling in the shuttle, and since filling or yarn that remains upon the filling carrier when it is discharged from the shuttle constitutes waste, it has been the constant effort of those familiar with looms to devise some character of feeler mechanism which shall be sufficiently sensitive both as to the presence and substantial absence of filling in the shuttle as to call for the change only when the filling has reached a degree of exhaustion such that the last pick of the shuttle will lay a full length of filling in the shed under proper tension.

Should the feeler mechanism call for a change of filling when there still remains sufficient for a number of picks, the waste incident to such change becomes excessive; and, on the other hand, should the feeler mechanism fail to call for a change of filling until the filling is completely exhausted, defective cloth will be woven, since no filling or only partial filling will be laid in the shed.

One of the objects of the present invention, therefore, is to provide a feeler mechanism for filling replenishing looms which shall be sensitive both to the presence and substantial absence of filling and to call for a change only when sufficient filling remains in the shuttle to properly lay the last pick of filling under proper tension.

In accordance with the present invention, the feeler mechanism comprises a feeler of the tilting or filling fork type which is mounted to enter through the side of the shuttle on a detecting beat and to indicate by its tilting or non-tilting condition the amount of filling still remaining in the shuttle, and such feeler is associated with a train of mechanism for calling a replenishment of filling when that in the shuttle has reached substantial exhaustion.

The invention and new combination of parts will best be made clear from the following description and the accompanying drawings of one good form thereof.

In the drawings:

Fig. 1 is a perspective view of portions of a loom at the feeler side thereof provided with the present invention;

Fig. 2 is a sectional elevation showing more particularly the feeler mechanism and the relation of parts when a working supply of filling is in the shuttle on a detecting beat;

Fig. 3 is a similar sectional elevation showing the relation of parts when the filling is substantially exhausted on a detecting beat;

Fig. 4 is a plan view of the feeler and some of its associated parts; and

Fig. 5 is a detached detail showing more particularly the feeler actuating means to cause replenishment of filling when the filling in the shuttle is substantially exhausted.

The filling replenishing mechanism which is controlled by the present invention is not herein shown and described because the details thereof form no essential part of the present invention and are now well understood by those familiar with filling replenishing looms.

The loom frame 1 may be of usual construction and at the front thereof is an arm 2 which rises from the usual transverse or rock shaft which extends to the opposite side of the loom for controlling the operative condition of the replenishing mechanism. Pivotedly mounted on the arm 2 at 3 is the actuator 4 to the rear end portion of which is pivoted at 5 a finger 6 which is adapted to be engaged at times by the cam follower 7. The finger 6 is provided with a projecting portion 8 under which extends the arm 9 of the bell crank lever 10 pivotally mounted at 11 on the bracket arm 12 secured to the shipper stand, as usual. The bell crank lever 10 has extending therefrom the pin 13 to which is connected the transmitter 14 which is under the control of the feeler mechanism presently to be described. A stop 15 is normally in engagement with the lower arm of the bell crank to limit its swinging movement in one direction.

Mounted upon the shipper stand is the bracket 16 which is located back of the shipper stand and secured in place by suitable adjusting bolt 17. If desired, in some cases the arm 12 on which the bell crank lever 10 is mounted, may be secured to the bracket 16, although this particular construction is not essential.

Mounted in suitable bearings 18, 19, Figs. 1 and 5, formed on the bracket 16, is the rock shaft 20, one end of which has secured thereto the arm 21 having a bifurcated end 22 which is engaged by a pin 23 extending from the cam follower, with the result that the rock shaft 20 is given movement from the cam follower.

Loosely mounted upon the rock shaft 20 is a finger 24 which is normally under the influence of a spring 25, one end of which at 26 is secured to the rock shaft, and the other end 27 of which is secured to the arm 24. To limit the action of the spring 25 upon the finger 24 a suitable stop is provided and, as indicated in Fig. 5, this may be constituted by a pin 28 carried on an arm 29 secured to the rock shaft 20, the effect being that the finger 24 while movable with the rock shaft 20, is, nevertheless, yieldingly mounted for movement in one direction, which in the present instance of the invention, permits the finger to come to rest when the end portion of the finger is moved frontwardly. The finger 24 has secured to its top portion an actuating member 30, the front end portion of which has a shoulder 31 which is adapted to engage the front tail portion of the tilting feeler should it fail to be tilted on a detecting beat, as will presently appear.

Mounted upon a suitable bracket 32 secured to a lateral projection 33 from the shipper stand is the feeler stand 34 in which is mounted a feeler carrier 35 the frontwardly extending stem portion 36 of which is under the influence of a spring 37 interposed between the front wall of the feeler stand and the shoulder 38 on the carrier, to normally hold the carrier in its rearward position.

On the rear end portion of the carrier 35 the feeler is mounted, and, as shown, it is pivotally supported upon the horizontal axis 39, so that the feeler 40 may have a tilting movement in a vertical plane. Secured to and extending downwardly from the rear portion 41 of the feeler are the tines 42 of which there may be any appropriate number, three being shown in the present instance of the invention. To the front end portion of the tilted or weft fork feeler a weight 43 is secured, as indicated more clearly in Fig. 2, and such weight normally acts to hold the feeler in the position indicated in Figs. 1 and 3; that is, in its untilted position, and the weight 43 may be conveniently provided with a recess 44 adapted to be engaged by the shoulder 31 of the finger when the weft fork feeler fails to be tilted on a detecting beat. To prevent overthrow or overtilting movement of the tilting feeler, a guard or stop 45 extends over the top of the feeler above its horizontal pivotal support 39, whereby such stop

may limit the swinging or tilting movement of the feeler in either direction.

In accordance with the present invention, the tilting or weft fork feeler is to enter through the side of the shuttle and present its lateral surface above the ends of the tines for engagement with the filling and in order that this may take place the front wall of the shuttle box is provided with a recess 46 and, similarly, the front wall 47 of the shuttle is provided with a recess 48 whereby the tines of the vertical tilting feeler may pass into the shuttle on a detecting beat and present the lateral surface of the tines above the ends thereof for engagement with the mass of filling in the shuttle without injury to the filling. If at such time a working supply of filling is present in the shuttle, as indicated in Fig. 2, the mass of filling 49 on the filling carrier 50 will engage the tines of the tilting feeler between the ends thereof, which for identification may be termed their lateral surface, and cause it to be tilted in a vertical plane before the finger 24 is moved, or about at the time it is moved frontwardly, thereby lifting the front portion of the tilting feeler out of the path of the finger, so that the loom continues to run without replenishment of filling.

However, should the filling in the shuttle be substantially exhausted on a detecting beat, the tines will fail to tilt the feeler in its vertical plane, as hereinbefore described, whereupon the shoulder 31 of the finger will engage the feeler and move the feeler carrier frontwardly to initiate replenishment of filling.

The feeler carrier 35, as indicated in the present instance of the invention, is provided with a pin 51 which engages an arm 52 of a lever which is pivoted at 53 on a stand or bracket 54 which may be appropriately secured to the bracket 16 as by the bolt 55. The other arm 56 of the lever, pivoted at 53, is extended backward, as indicated in Fig. 1, and has secured thereto at 57 the end of the transmitter 14.

From the construction above described it will be apparent that the feeler is pivotally mounted upon the feeler carrier to tilt in a vertical plane about an axis that is above a horizontal plane passing through the longitudinal axis of the shuttle, as more clearly indicated in Figs. 2 and 3, and that the tines which extend downwardly from the tilting feeler will enter the shuttle and feel for the mass of filling in the shuttle. Should a working supply of filling be present on a detecting beat, the tilting or weft fork feeler will be tilted by frontward pressure against the lateral surface presented by the tines above their ends, as indicated in Fig. 2, and the loom will continue to run without replenishment, and since the tines engage the

filling along the lateral surface of the tines no injury to the filling results by the contact pressure. Should the filling be substantially exhausted, however, on a detecting beat, the 5 tines of the tilting feeler will not cause tilting movement of the feeler in its vertical plane, as indicated in Fig. 3, whereupon the shoulder 31 of the finger will engage the feeler and move the feeler and feeler carrier 10 frontwardly, with the result that through the train of mechanism comprising the transmitter and associated parts and including the arm 52, the finger 6 connected to the actuator 4 will be placed in operative relation with the operating member or cam follower 15 7 to thereby move the actuator frontwardly, turn the transverse or rock shaft and call for replenishment of filling.

The finger 24 with its shouldered portion 20 31 has its tail portion 30 extended rearward sufficiently far so that as the finger 24 moves frontward without engagement with the un-tilted feeler and as the lay goes back, the front end portion of the weight 43 of the 25 tilting feeler will ride upon the tail 30 so that it will not be caught backward of the finger 24.

The feeler mounted to swing about an axis in a vertical plane and at a point above 30 the horizontal plane passing through the longitudinal axis of the filling carrier, is sensitive both to the presence and absence of filling in the shuttle on a detecting beat, so that a minimum amount of filling may 35 be left upon the filling carrier in the shuttle when change of filling is called. The lateral faces of the tines 42 which engage the filling will not act upon the same with sufficient force to injure even the most delicate filling, 40 since the pressure which the filling exerts upon the tines serves merely to tilt the weft fork feeler and not to push the feeler carrier frontwardly.

In practice it is preferable to employ a 45 bunch on the filling carrier in the shuttle, so that the tines of the tilting feeler may co-operate with the bunch and call for a change of filling when the bunch itself has been depleted to a predetermined amount. While 50 the cooperation of the tilting feeler and bunch presents some advantages in minimizing waste, it is clear, of course, that the feeler mechanism constituting the present invention may be employed in connection 55 with filling carriers whereon there is no bunch.

What is claimed is:

1. In a feeler mechanism for looms, the 60 combination of a feeler carrier mounted for movement towards and from the front of the loom, a shuttle having the upper portion of one of its side walls cut away to form a feeler receiving passage, a tilting weft fork feeler mounted on the feeler car- 65 rier to extend downwardly transversely of

the shuttle and adapted to enter said feeler receiving passage to engage the mass of filling in the shuttle and to be tilted thereby on detecting beats until the filling is substantially exhausted, and means for moving the 70 weft fork feeler and feeler carrier frontwardly when the weft fork feeler fails to be tilted on a detecting beat.

2. In a feeler mechanism for looms, the 75 combination of a feeler carrier mounted for movement towards and from the front of the loom, a tilting weft fork feeler mounted on the feeler carrier and having tines that enter through the side of the shuttle to cause the lateral surface of the tines to engage the mass of filling in the shuttle and cause tilting movement of the weft fork feeler until the filling is substantially exhausted, means for engaging the weft fork 80 feeler when it fails to be tilted on a detect- 85 ing beat to move it frontwardly for effecting replenishment of filling.

3. In a feeler mechanism for looms, the 90 combination of a shuttle having the upper portion of one of its side walls cut away to 95 form a feeler receiving passage, a tilting weft fork feeler mounted to enter said passage in the side of the shuttle and having tines the lateral surface of which engages the mass of filling and causes tilting move- 100 ment of the weft fork feeler until the filling is substantially exhausted, and means for effecting replenishment of filling when the weft fork feeler fails to be tilted by the filling within the shuttle on a detecting beat. 100

4. In a feeler mechanism for looms, the 105 combination of a tilting weft fork feeler mounted to enter through the side of the shuttle and having spaced rigidly connected tines which engage the mass of filling and cause tilting movement of the weft fork feeler until the filling is substantially exhausted, a rock shaft actuated from a going part of the loom, a finger mounted on the rock shaft and adapted to engage and move 110 the weft fork feeler frontwardly when it fails to be tilted by a mass of filling within the shuttle on a detecting beat.

5. In a feeler mechanism for looms, the 115 combination of a feeler carrier, a tilting weft fork feeler mounted on the carrier and having tines to enter through the side of the shuttle and present their lateral surface for engagement with the mass of filling therein and cause the weft fork feeler to be 120 tilted on a detecting beat by a working supply of filling, means for engaging the weft fork feeler when it fails to be tilted by the mass of filling in the shuttle on a detecting beat, and actuating devices for said means to 125 cause the weft fork feeler and feeler carrier to be moved frontwardly and effect replenishment of filling.

6. In a feeler mechanism for looms, the 130 combination of the cam follower, a rock

- shaft actuated thereby, a feeler carrier mounted for movement towards and from the front of the loom, a feeler pivotally mounted on the carrier to swing in a vertical plane and having downwardly extending rigidly connected tines to enter through the side of the shuttle and engage the mass of filling therein to cause the feeler to be tilted in a vertical plane until the filling is substantially exhausted on a detecting beat, and a finger mounted on the rock shaft to engage the feeler and move it and the feeler carrier forwardly when the tines fail to tilt the feeler.
- 15 7. In a feeler mechanism for looms, the combination of a feeler carrier mounted for movement towards and from the front of the loom, a feeler pivotally mounted on the carrier to swing in a vertical plane and having tines which enter through the side of the shuttle to engage their lateral surface with the mass of filling in the shuttle and cause tilting movement of the feeler in the vertical plane until the filling is substantially exhausted on a detecting beat, a finger for engaging and moving the feeler forwardly when the tines fail to tilt the feeler, and means actuated by forward movement of the feeler to effect replenishment of filling.
- 20 8. In a feeler mechanism for looms, the combination of a feeler carrier mounted for movement towards and from the front of the loom, a feeler pivotally mounted on the carrier to swing in a vertical plane and having tines which enter through the side of the shuttle to engage their lateral surface with the mass of filling in the shuttle and cause tilting movement of the feeler in the vertical plane until the filling is substantially exhausted on a detecting beat, means normally acting to hold the feeler from tilting move-
- 25
- 30
- 35
- 40

ment, a finger for engaging and moving the feeler forwardly when the tines fail to tilt the feeler, and means actuated by forward movement of the feeler to effect replenishment of filling. 45

9. In a feeler mechanism for looms, the combination of a shuttle having one of its side walls provided with an open slot extending downwardly from the upper edge of the side wall, a feeler carrier, a feeler pivotally mounted on the carrier to swing in a vertical plane about an axis above the horizontal plane passing through the longitudinal axis of the filling carrier in the shuttle and having downwardly extending rigidly connected tines to enter through the upwardly open slot of the shuttle and engage their lateral surface with the mass of filling in the shuttle on a detecting beat to cause tilting movement of the feeler until the filling is substantially exhausted, and means for engaging and moving the feeler forwardly when the feeler fails to be tilted on a detecting beat. 50

10. In a feeler mechanism for looms, the combination of a feeler mounted for swinging movement in a vertical plane and having downwardly extending tines which enter through the side of the shuttle to engage their lateral surface above the ends of the tines with the mass of filling in the shuttle to cause tilting movement of the feeler in a vertical plane until the filling is substantially exhausted on a detecting beat, and means for effecting replenishment of filling when the tines fail to tilt the feeler in the vertical plane on a detecting beat. 55

In testimony whereof, I have signed my name to this specification.

EDWARD A. CUNIFF.
